UNITED STATES PATENT OFFICE.

JAMES D. HAYES, OF DALLAS, TEXAS, ASSIGNOR, BY DIRECT AND MESNE ASSIGNMENTS, OF ONE-THIRD TO BEVERLY WHITE, OF CHICAGO, ILLINOIS, AND ONE-THIRD TO PAUL HUNTER, OF SAN ANTONIO, TEXAS.

PHOTOGRAPHIC BATH TANK.

Application filed November 30, 1925. Serial No. 72,275.

My invention relates to improvements in photographic bath tanks, and it consists in the combinations, constructions, and arrangements herein described and claimed.

- 5 In the developing of pictures, the negatives are immersed in a tank of water and the water is allowed to flow into the tank by means of the open top of the tank, and then to flow out over the edges of the tank.
- 10 Due to the inertia of the water, the water disposed at the bottom of the tank comes to rest and therefore the portions of the negatives disposed in this water will not be washed free of chemicals as are the portions 15 of the negatives disposed adjacent to the running water. If a negative is not entirely cleaned of chemicals, it will continue to fade out after it has been removed from the tank, even though this fading out will be extremely slow. This is the reason why some 20 negatives after being filed away for six months or a year or longer will have a portion thereof blurred or slightly faded, while the other portion is clear.
- 25 It is obvious that if the water were caused to flow along the entire surfaces of the negatives for a length of time sufficient to entirely wash away the chemicals, a print would result that would last indefinitely 30 without fading.

The principal object of the present invention is to provide a photographic bath tank which causes the water to flow over the entire surface of each negative, whereby all 35 of the chemicals will be washed away, thus providing a negative which will last indefinitely without fading.

A further object of my invention is to provide a photographic bath tank which is 40 extremely simple in construction, durable and efficient for the purpose intended.

Other objects and advantages will appear in the following specification, and the novel features of the invention will be particularly 45 pointed out in the appended claim.

My invention is illustrated in the accompanying drawings, forming a part of this application, in which—

Figure 1 is a vertical section through the 50 device, and

Figure 2 is a plan view of Figure 1.

In carrying out my invention, I provide a bath tank 1 which is divided into two compartments A and B. The compartment A

has its walls 2 and 3 projecting above the 55 top of the compartment B for a purpose hereinafter described. The partition 4 dividing the tank into the two compartments terminates a short distance above the bottom 50 of the tank.

In the compartment B, I dispose a number 60 of negatives 6 and mount them in the manner shown. Figure 2 shows how the strips 7 supporting the negatives straddle the upper edges 8 of the compartment B. 65 These strips support the negatives 6.

From the foregoing description of the various parts of the device, the operation thereof may be readily understood. Water is conveyed to the compartment A from a 70 faucet 9 and this water will build up in the compartment A and will flow through the aperture 10 into the compartment B. After the compartment B has been entirely filled with water, the water will continue to rise 75 in the compartment A until it establishes a head of water that will cause the water in the compartment B to overflow in the manner shown in Figure 1. It will be seen from this construction that the entire body 80 of water in the compartment B is constantly changed due to the fact that the water is admitted at the bottom of the compartment B and overflows at the top. The flow of the water is indicated by the arrows, and the 85 arrows show how the water flows along the entire surfaces of all of the negatives 6.

The negatives are kept immersed in the water a sufficient length of time to permit the water to wash away all of the chemicals 90 from the negatives. The entire negative will be washed instead of only a portion thereof due to the novel arrangement of the compartments A and B and the aperture 10. In this way, all of the chemicals will be 95 washed from the entire surface of each negative, thus providing negatives which will never fade.

I claim:

A device of the type described comprising 100 a tank having a water-receiving compartment and a negative-washing compartment adapted to receive negatives, said water-receiving compartment extending above said negative-washing compartment, and a partition 105 disposed between said compartments and extending from the upper edge of said water-receiving compartment to a position

a short distance from and in parallel relation with the bottom of said tank, whereby the water in the water-receiving compartment may be maintained at a level above the upper edge of the negative-washing compartment and the force of the water within the water-receiving compartment will force

the water from the water-receiving compartment beneath said partition and along the bottom of said tank where it will be allowed to raise upwardly on both sides of the negatives and over the upper edges of the negative-washing compartment. 10

JAMES D. HAYES.
